by Walter Allen, ATTY.

UNITED STATES PATENT OFFICE.

GEORGE W. TEASDALE, OF ST. LOUIS, MISSOURI.

CARTON.

933,599.

Specification of Letters Patent. Patented Sept. 7, 1909.

Application filed January 12, 1909. Serial No. 471,902.

To all whom it may concern:

Be it known that I, GEORGE W. TEASDALE, a citizen of the United States, residing in the city of St. Louis and State of Missouri, have invented certain new and useful Improvements in Cartons, of which the following is a full, clear, and exact description, reference being had to the accompanying drawings, forming a part of this specification.

10 My invention relates to that character of containers made of pasteboard or heavy paper, an example of which is to be found in Letters Patent of the United States, No. 15 899,922, issued to me September 29, 1908, and upon which my present invention is in the nature of an improvement.

The carton shown and described in the patent mentioned is a very desirable one for 20 the reasons pointed out in the patent; but due to the arched lining sheet therein being permanently attached at its ends to the shell of the carton, it is impractical to fold the empty carton for shipment previous to its 25 being put into use as a container, and inasmuch as the folding of the carton for shipment when empty saves expense of shipment, I have provided a construction that will permit of such folding and which construction 30 constitutes the subject matter of my present application.

A further object of my present invention is to provide means whereby the sides and 35 ends of the carton may be held from collapsing when unfolded for use, and also whereby air, moisture, and rays of light may be approximately excluded from the interior of the carton to prevent their access thereto into to the detriment of the merchandise 40 packed in the carton.

Figure I is in part a perspective view and in part a vertical cross section of my carton. Fig. II is a vertical longitudinal section through the carton. Fig. III is a horizontal section. Fig. IV is a cross section of the carton in folded or collapsed condition. Fig. V is a cross section near one end of the carton in a folded condition.

In the accompanying drawings: 1 designates the shell of my carton which is provided at its ends with outer closing flaps 2 adapted to be folded onto each other and secured together in any suitable manner, such as by the provision of tongues upon one 55 flap that are adapted to enter into engagement with the flap mating therewith in a

usual manner, or by pasting the flaps to each other.

Within the shell of the carton is a reinforcing or lining sheet 5 that is attached at 60 one end to the carton shell, but is free of connection with said shell at its other end. This lining sheet is adapted to be arched or bowed into the condition illustrated in the drawings by means to be presently described 65 whereby the sheet is caused to serve a purpose similar to a like sheet in my patent hereinbefore mentioned.

3 designates a guard or presser sheet that is located within one end of the carton shell 70 and is provided with side flanges 4 and 4', one of said flanges, for instance at 4, being secured in a suitable manner to a side of the carton shell and being preferably pasted thereto. The other flange is free of connection 75 to the carton shell, and, therefore, the guard or presser sheet may extend outward through the open end of the carton shell when the carton is folded and be pressed into the carton shell to hold said shell extended when it is unfolded, and also serve to press against the free ends of the lining sheet 5 whereby said lining sheet is arched, as seen in the drawings, and maintained in an arched condition. It will be seen that 80 inasmuch as the lining sheet is free of pressure when the guard or presser sheet is extended through the open end of the carton shell, said lining sheet may lie flatly against the walls of the shell and permit folding of 85 the carton.

6 designates an auxiliary guard or presser sheet that is provided at its ends with outward end flanges 7 and 8, (see Fig. II,) one of these flanges, for instance flange 7, 95 being pasted or otherwise secured to an end wall of the carton shell, and the other flange being free of connection to the carton shell. When the carton is folded, the free end of the auxiliary guard or presser sheet extends 100 outwardly from the carton shell and the end secured to the shell remains intact therewith; and when the carton is unfolded, the auxiliary guard or presser sheet occupies a position within the carton shell and rests against 105 the guard or presser sheet 3, (as seen in Figs. I and II,) serving to hold the sheet 3 in its proper position when the closing flaps of the carton are secured in their closed positions.

As will be seen by the construction described, the guard or presser sheets 3 and 6

serve to exert pressure against the lining sheet 5 at its free ends to maintain this sheet in a bulged condition, as desired, whereas when said carton or presser sheets 5 are extended from the interior of the carton shell, the carton may be readily folded due to the lining sheet being at this time permitted to move outwardly and into close contact with the walls of the carton shell. 10 It will be further seen that the guard or presser sheets 3 and 6 serve to exclude air, moisture, rays of light, and dust from the interior of the carton to the detriment of the contents placed therein.

15 I claim:

1. A carton comprising a shell, a main guard sheet hinged to said shell and adapted to be folded into said shell, and an auxiliary guard sheet hinged to said shell and adapted 20 to be folded into said shell, substantially as described.
2. A carton comprising a shell, a main guard sheet hinged to said shell and adapted to be folded into said shell, and an auxiliary guard sheet hinged to said shell and adapted 25 to be folded into said shell; said guard sheets being hinged to said shell transversely of each other.
3. A carton comprising a shell, a lining

sheet within said shell attached at one of its 30 ends to the shell and free of connection to the shell at its other end, and a guard or presser sheet adapted to bear against the free end of said lining sheet.

4. A carton comprising a shell, a lining 35 sheet within said shell attached at one end to the shell and free of connection with the shell at its other end, and a guard or presser sheet hinged to said shell and adapted to be folded into said shell to bear against the 40 free end of said lining sheet, substantially as described.

5. A carton comprising a shell, a lining sheet within said shell attached at one end to the shell and free of connection with the 45 shell at its other end, a guard or presser sheet hinged to said shell and adapted to be folded into said shell to bear against the free end of said lining sheet, and an auxiliary guard or presser sheet hinged to said shell and adapted to be folded into said shell to bear against said first named guard or presser sheet, substantially as described. 50

GEO. W. TEASDALE.

In the presence of—

H. G. COOK,
E. B. LINN.
